STRIPING INSTRUMENT

John M. Christman, Detroit, Mich., assignor to
Packard Motor Car Company, Detroit, Mich.,
a Corporation of Michigan

Application June 28, 1929. Serial No. 374,363

7 Claims. (Cl. 91—62.6)

This invention relates to striping instruments, and more particularly to motor driven striping instruments.

An object of the invention is to provide an instrument for applying a stripe of paint or lacquer to a surface.

Another object of the invention is to provide an instrument for applying stripes to a surface where the use of a guide or straight edge is impossible due to the restricted space for operation.

Another object of the invention is to provide an instrument having a motor operated feed for delivering paint or lacquer from a container to a nozzle, and means associated therewith for controlling the operation thereof.

Another object of the invention is to provide a striping instrument having a positive feed means for delivering paint or lacquer from a container to the nozzle of the instrument, and means readily accessible to the operator for controlling the feed means.

Still a further object of the invention is to provide a striping instrument having a motor operated pump for delivering paint or lacquer from a container to a nozzle, and a brake for the pump having actuating means for varying the speed of the pump, or for stopping the pump as may be desired in the manipulation of the instrument.

A still further object of the invention is to provide a motor driven striping instrument which is highly efficient in operation and yet of marked simplicity as a whole, and in respect to its component parts, so that its manufacture may be economically facilitated both regarding parts and their assembly.

Other objects of the invention will appear from the following description taken in connection with the drawing, which forms a part of this specification, and in which:

40. Figure 1 is a longitudinal sectional view of an instrument embodying the invention.

Figure 2 is a sectional view substantially on line 2—2, Figure 1, and

45. Figure 3 is a sectional view substantially on line 3—3, Figure 1.

Referring to the drawing for more specific details of the invention, 10 represents a sleeve having an inturned flange 11 providing an axial bore 12. The sleeve is internally threaded as indicated at 13, and is provided with a boss 14 having a bore 15. A container 16 is supported in the bore 15 and the container is provided with a cap 17, having the conventional vent 18.

50. A disk 19 positioned in the sleeve 10 bears against the flange 11. The disk 19 has formed

integral therewith a sleeve 20, axially bored as indicated at 21, and mounted for rotation in the bore 15 is a shaft 22. The shaft 22 is suitably connected to a spring motor 23 having the conventional winding key 24. Positioned in the disk 19 is a passage 25 leading from the bore 15 to the intake port 26 of the pump mechanism.

The pump mechanism is preferably of the gear type comprising a plurality of gears 28, one of which is suitably keyed to the shaft 22. As shown, the gears 28 are mounted in a disk 29 having overlapping transverse bores in which the gears are positioned in intermeshing relation with the intake 30 registering with the port 26 and the outlet 31 registering with a passage 32 positioned in a disk 33 which covers the pump and the disk 29 in which the pump is positioned.

The disks 19, 29 and 33 are secured to each other and to the flange 11 by means of a pin 34. This pin also secures in position a nozzle 35. As shown, the nozzle 35 is provided with a flange 36 which fits snugly in the sleeve 10, and is clamped therein together with the disks 19, 29 and 33 by means of a nut 37 threaded in the sleeve.

The nozzle 35 is provided with an axial bore 38 adapted to register with the passage 32 communicating with the outlet of the pump, and positioned longitudinally in the nozzle for smooth reciprocation is a shaft 39 one end of which extends through the disk 33 and engages a face on one of the gears 28. The other end of the shaft is loosely pivoted to prevent binding as indicated at 40 to a bell crank lever 41 having one end pivoted to the nozzle as indicated at 42, and the other end engaging a coil spring 43 positioned in a recess 44 in the wall of the nozzle. The shaft 39 is actuated by the spring 43 to bear upon one of the gears 28 with sufficient pressure to control the motor 23.

In operation, assuming that the container 16 is filled with paint, lacquer, or the like, and that the motor 23 has been wound for operation; the discharge end of the nozzle is applied to the surface to be operated upon, and the lever 41 is actuated by the thumb or forefinger to disengage the shaft 39 from the gear; whereupon the motor immediately sets the pump mechanism in operation to draw the paint or lacquer from the container 16 through the passage 25 to and through the intake port, through the pump and discharges it through the outlet port 32 and the nozzle.

The paint or lacquer is discharged from the nozzle in a constant flow and as it is discharged, the instrument is moved across the surface to be operated upon. It is to be understood that the

speed of the pump may be readily regulated to discharge the quantity of paint desired by varying the pressure on the bell crank lever 41, or that the lever may be released to stop the operation of the pump. Hence the pump mechanism may be operated to deliver a predetermined quantity of paint from the container to the discharge end of the nozzle.

One of the outstanding features of this invention is the provision of a striping instrument having a nozzle of small cross sectional area, permitting operation in restricted areas. Another important feature is the means for controlling the operation of the feeding mechanism at a point readily accessible to the operator, and a further important feature is the provision of an instrument having a motor driven feeding mechanism.

Although this invention has been described in connection with certain specific embodiments, the principles involved are susceptible of numerous other applications that will readily occur to persons skilled in the art. The invention is, therefore, to be limited only as indicated by the scope of the appended claims.

Having thus described the various features of my invention, what I claim as new and desire to secure by Letters Patent is:

1. A striping instrument comprising a container, a nozzle, a pump connected between the container and the nozzle, means for operating the pump, and manually actuated brake means positioned on the nozzle and engageable with the pump for controlling the operating speed thereof.

2. A striping instrument comprising a container, a nozzle, a pump connected between the container and the nozzle, a motor for driving the pump, and a manually operated brake mechanism mounted on the nozzle and engageable directly with the pump to control the speed thereof.

3. A striping instrument comprising a container, a nozzle, a feeding means intermediate the container and the nozzle, a motor for op-

erating the feeding means to deliver paint from the container to the nozzle, a brake mechanism for the pump positioned in the nozzle, and a manually operated lever for actuating the brake readily accessible to the operator.

80

4. A striping instrument comprising a nozzle, a pump associated with the nozzle in a relation to feed fluid therethrough, a motor connected to operate the pump, a brake element directly engageable with the pump, and manually operable mechanism carried by the nozzle and connected to control the brake element.

85

5. A striping instrument comprising a container, a nozzle, a rotary pump intermediate the container and the nozzle, a motor for operating the pump, a rod carried by the nozzle and engageable with the pump to control the speed of rotation thereof, and operating means connected with the rod, said means being adapted to move the rod toward and away from the pump.

90

6. A striping instrument comprising a nozzle, a gear pump associated with the nozzle in a relation to feed fluid therethrough, a motor connected to operate the pump, an axially movable rod carried by the nozzle and engageable with one of the pump elements to brake the speed of rotation thereof, and a lever pivoted to the nozzle and to the rod, said lever being manually operable to move the rod axially.

95

7. A striping instrument comprising a nozzle, a rotary pump associated with the nozzle in a relation to feed fluid therethrough, a motor connected to operate the pump, an axially movable rod engageable with the pump to brake its rotation, a lever pivoted to the nozzle and to the rod, said lever being adjustable to move the rod axially, and a spring intermediate the lever and the nozzle exerting a force against the lever to normally place the rod in braking relation with the pump.
